L. F. CLARK,
INTERNAL COMBUSTION ENGINE,
APPLICATION FILED AUG. 2, 1916.

Patented Aug. 13, 1918.

2 SHEETS—SHEET 2.

UNITED STATES PATENT OFFICE.

LOUIS FRANCIS CLARK, OF WILMINGTON, DELAWARE, ASSIGNOR OF ONE-HALF TO
IRVING A. ANDERSON, OF GRAND RAPIDS, MICHIGAN.

INTERNAL-COMBUSTION ENGINE.

1,275,848.

Specification of Letters Patent. Patented Aug. 13, 1918.

Application filed August 2, 1916. Serial No. 112,874.

To all whom it may concern:

Be it known that I, LOUIS FRANCIS CLARK, a citizen of the United States of America, residing at Wilmington, in the county of New Castle and State of Delaware, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines, and especially engines of the type known as the four-cycle engine. It is the object and purpose of the present invention to provide in a novel construction a means for rotating the piston of the engine about its longitudinal axis within its cylinder as said piston reciprocates in the cylinder. My former construction is shown in Patent No. 1,106,365 issued Aug. 11, 1914 and the present invention is concerned with improvements in construction to attain the same result but more efficiently, and with a construction of greater durability. In the present invention I do away with frictional contact between the reciprocating piston and the member which causes the piston to rotate as it is reciprocated substituting therefor a novel construction and arrangement of parts entirely eliminating such frictional engagement. For an understanding of the engine construction and operation of the same, reference may be had to the accompanying drawings in which:

Figure 1 is a vertical section of an engine in which my invention is embodied, said section being taken through the axis of the crank shaft.

Fig. 2 is a vertical section taken through the cylinders of the engine and showing the position of the piston in one portion of its travel, substantially at its lowermost point in the cylinder.

Fig. 3 is a view similar to Fig. 2 the piston being at a higher elevation in the cylinder.

Fig. 4 is a vertical section through the engine transversely of the crank shaft.

Fig. 5 is another view similar to that shown in Figs. 2 and 3 with the piston in still another position with respect to the cylinder.

Figs. 6, 7, and 8, are, respectively, horizontal sections taken on the lines 6—6 of Fig. 5, 7—7 of Fig. 3 and 8—8 of Fig. 2.

Like reference characters refer to like parts throughout the several views of the drawings.

In the construction of the engine the usual crank case 1 is provided having bearings in which the crank shaft 2 is journaled. The crank shaft carries the usual fly-wheel 3. Above the crank case a cylinder 4 is secured in which a piston 5 reciprocates.

A connecting rod 6 at its lower end is connected to the wrist-pin 7 of the crank shaft, the lower end of this connecting rod being provided with a journal bearing 8 which passes around the wrist-pin. This bearing is of special construction being enlarged and having upper and lower spaced apart ears 9 and 10 projecting laterally to one side of the wrist pin 7 and containing bushings in which is rotatably mounted a substantially vertical shaft 11 which lies along side the connecting rod 6 as shown. At its lower end a nut or other equivalent head 12 is used to bear against the underside of the ear 10 while between ears 9 and 10 a worm-gear 13 is keyed to the shaft meshing with a worm 14 secured to and rotatable with the wrist-pin 7. A sleeve 15 covers the worm and protects it from the journal 8 at the lower end of the connecting rod.

The upper end of shaft 11 is threaded into or otherwise suitably secured to a yoke 16 interposed between the spaced apart sides of which is a cylindrical pin 17 on which is placed a block 18. Threaded into opposite sides of the block are pins 19 which extend into bushings 20 carried by the piston 5. The pins 19 are positioned at right angles to pin 17 there being provided in this manner a universal joint. A sleeve 21 projects downwardly from yoke 16 in the lower portion of which a head 22 of the formation shown is located, this head being carried at the upper end of the connecting rod 6 and serving as a seat for conical roller bearings

23 which are interposed between said head 100 and a member 24 located beneath the yoke 16 and in the upper part of the sleeve 21. The sleeve 21 and member 24 are secured in any suitable manner to the yoke 16 and while shown as separate parts may, if desired, be formed integral therewith. With this construction it is apparent that the piston makes one reciprocation with each rotation of the crank shaft and at the same time the piston turns about a vertical axis in the cyl-

inder. The gearing shown at 13 and 14 is such that with a complete rotation of the crank shaft the shaft 11 completes one-half of a revolution. In a four-cycle engine two complete rotations of a crank shaft are necessary to carry out the cycle and, accordingly, with each cycle there is a complete rotation of the shaft 11 and the piston 5 is turned around once in the cylinder 4.

10 For the admission of the explosive mixture to the cylinder and the escape of the exhaust gases therefrom an inlet port 26 and an exhaust port 25 are provided in the lower part of the cylinder being covered at all 15 times by the piston. The pipe 25^a may carry the exhaust gases away and a similar intake pipe (not shown) may be connected between the carburetor and the inlet port 26. The piston is provided with ports 27, 28, and 29, 20 in one side which communicate with a passage 30 segmental in horizontal section and open at its upper end through the piston head. The piston is provided with the usual 25 rings as is common in engines of this character.

The operation of the engine is as follows: With the piston at the end of its working stroke, that is, at its lowermost position in the cylinder and about to begin an upward 30 and exhaust stroke as shown in Figs. 5 and 6, the port 28 in the piston is substantially opposite the exhaust port 25 in the cylinder. As the piston rises it will as previously described rotate the ports in the side of the 35 piston following an upward spiral path so that ports 28 and 29 pass by the exhaust port and allow the exhaust gases within the cylinder to escape. The position of the piston at the end of the exhaust stroke is shown 40 in Fig. 3 and with the continuation of its movement the intake stroke follows. In doing this the piston travels downwardly 45 rotating at the same time and exposing the ports 29, and 27 in succession to the inlet 26, the suction produced by the downward 50 movement of the piston drawing in a fresh charge of the explosive mixture. The piston at the completion of the intake stroke is located as shown in Fig. 2. The following 55 stroke of the cylinder is the compression stroke at the end of which the charge is ignited in any suitable manner driving the piston downward in its working stroke. During the compression and working 60 strokes ports 27, 28, and 29 are opposite the solid wall of the cylinder and no gases can escape.

From the foregoing it will be apparent that this engine is of very simple construction and comparatively cheap to make, the usual valves being eliminated. Furthermore with a construction of this character the two strokes of the cylinder, in which the

greatest force is on the piston namely, that of compression and that after the charge is fired, are borne entirely by the connecting rod, no stress being transmitted to the shaft 11. The intake stroke is made possible through the connection of the shaft 11 to the universal joint which is attached to the piston. Otherwise the connecting rod at its upper end might dissociate from the piston, not being directly connected thereto. In the exhaust stroke the resistance to the upward movement of the piston caused by the exhaust gases is imparted to the connecting rod which takes care thereof. Accordingly the construction is one in which the major stresses occurring in the engine are taken care of by the connecting rod and substantially the only work that the shaft 11 has to do is to rotate the piston as it reciprocates in the cylinder.

I claim:

1. In combination, a piston, a universal joint construction carried by the piston including one member pivotally connected to the piston and a second member pivotally connected to the first member to turn about an axis at right angles to the axis of pivotal connection of the first member to the piston, a shaft connected to and depending from said second member, a sleeve open at its lower end depending from the second member, a crank shaft, a connecting rod connected to the crank shaft and loosely entering into the lower end of the sleeve, the upper end of the connecting rod and the lower side of the second member being formed with conical bearing surfaces, tapered rollers interposed between the upper end of the connecting rod and lower side of the second member, and means to turn the shaft about its axis on rotation of the crank shaft, substantially as described.

2. In combination, a piston, two members pivotally connected together, a pivotal connection between one member and the piston, the axis of which lies at right angles to the axis of the pivotal connection between the two members, a sleeve open at its lower end and depending from the other member, a crank shaft, a connecting rod attached at its lower end to the crank shaft and extending at its upper end into the sleeve, anti friction bearings between the upper end of the connecting rod and the lower side of said second member, a shaft lying alongside the connecting rod, passing loosely through the same at its upper end and connecting to said second member, and means operatively connecting the lower end of the shaft to the crank shaft whereby said shaft is rotated with the rotation of the crank shaft.

In testimony whereof I affix my signature.

LOUIS FRANCIS CLARK.
